WARP BEAM

Robert V. Olson and William B. Swenson, Attleboro, Mass., assignors to Mossberg Pressed Steel Corporation, a corporation of Massachusetts

Application January 30, 1936, Serial No. 61,567

14 Claims. (Cl. 242—124)

This invention relates to beams, and more particularly to a yarn beam of the type used for the winding of warp threads and having a tubular metal beam barrel provided with screw-threaded portions for mounting the head members; and has for one of its objects the provision of means axially movable with reference to the body of the beam to cover at all times the threaded portions thereof over which the warp may be wound 10 and to prevent any yarn from becoming lodged therein.

Another object of the invention is to provide means for covering the threaded portions of the beam barrel which may be moved axially back and forth along the beam barrel body without rotation thereon as the head member is adjusted in desired positions along the barrel body member by relative rotation of said members.

A further object of the invention is the provision of means attached loosely to a rotatably mounted head member whereby said means may be moved lengthwise along the beam barrel member without being turned thereon to cover the screw-threads on the body member as the head member is freely turned by relative rotation with respect to the body member.

A still further object of the invention is the provision of means whereby the clamping device carried by the hub of the beam head is prevented from opening too far during disengagement of the head from the body member and axial adjustment therealong so that the yarn engaging face of the head will be maintained square with the barrel and run true when the head is adjusted axially and clamped in desired positions along the threaded portions of the beam barrel.

With these and other objects in view, the invention consists of certain novel features of construction, as will be more fully described and particularly pointed out in the appended claims.

In the accompanying drawing:

Fig. 1 is a side elevation of a yarn warp beam embodying the invention;

Fig. 2 is an end view of the beam shown in Fig. 1;

Fig. 3 is a fragmentary longitudinal sectional view of a portion of the beam shown in Fig. 1 taken on the line 3—3 of Fig. 2 illustrating the relative relationship of the head member, sleeve and threaded tubular beam barrel;

Fig. 4 is a detail view in vertical section of the clamping device shown on the head member in Fig. 3;

Fig. 5 is a detail sectional view of the face plate of the head member shown in Fig. 3;

Fig. 6 is a fragmentary view of a portion of the threaded tubular beam barrel;

Fig. 7 is a detail view of the slidable sleeve shown in Fig. 3 loosely mounted in the face plate;

Fig. 8 is a fragmentary longitudinal sectional view of a modification of the present invention;

Fig. 9 is a cross-sectional view taken on the line 9—9 of Fig. 8; and

Fig. 10 is a fragmentary longitudinal sectional view of another modified form of beam embodying the invention.

In the construction of beams for yarn, such as warp beams or the like, one type of beam construction heretofore employed consists of a hollow beam body member formed of sheet steel and having threaded end portions on each of which is mounted an adjustable beam head which has threaded engagement with the screw-threads of the beam body portions and is adapted to be clamped in desired adjusted positions therealong. However, in the use of such a beam construction it is particularly desirable that the screw-threads of the respective portions of the beam body extending inwardly therealong from the yarn engaging face portion of the head members and disposed the beam heads be completely covered at all times regardless of the position of adjustment of the head members in order to prevent yarn from lodging in the threads and to avoid breakage of the inner layers of the warp; and in order that this result may be accomplished satisfactorily, we have provided means cooperating with a head member and movable axially along the body of the beam without turning thereon upon relative rotation of the head member with reference to the beam body member for causing said head to move therealong to the different adjusted positions, and we preferably make said thread covering means of such form and length that it will embrace the body member of the beam and extend inwardly therealong lengthwise from the yarn engaging face of the head member to wholly cover the threads which may be disposed between the heads and regardless of the relative movement of the heads to different adjusted positions; and as a specific embodiment of our invention we may utilize a sleeve loosely related to the head member and slidably axially along the body of the beam without turning thereon and over the threads as the head is relatively rotated with reference to the beam body member; and as a further feature of the invention we have provided means which is associated with a clamping device carried by the head member for limiting the extent of unclamping movement thereof to a pre-

determined amount whereby the head may be disengaged, adjusted axially along the body member of the beam, and clamped in desired positions thereon with the yarn engaging face of said head member being positioned at all times in proper truth with the beam barrel; and the following is a detailed description of various specific embodiments of this invention, illustrating the preferred means by which these advantageous results may be accomplished.

With reference to the drawing, 10 designates the barrel or body member of the warp beam and is of generally cylindrical tubular form, made of sheet metal such as sheet steel, the barrel being provided with spaced threaded portions 11 and 12 preferably located at its ends on which are mounted a pair of opposed beam head members 13 and 14, respectively, which are adjustable along the length of the body member of the beam upon relative rotation of the members for accommodating warps of different widths.

Each of the head members 13 and 14 may comprise a face portion 15, which may be formed of an annular metal plate, having a hub 16 projecting from one side thereof and integrally attached to the plate by radial strengthening ribs 17 of any desired number suitably secured to the plate 15 at their outer end by welding or the like. The hub 16 is formed with a suitable opening to receive the body member of the beam which opening is suitably threaded as at 18 to engage the screw-threads on the beam barrel portions 11 and 12, respectively, whereby rotation of the beam heads relative to the body member causes axial movement of the head member along their respective portions of the beam barrel. The hub 16 is split as at 20 with its ends spaced apart. One end portion is provided with a threaded ear 21 while the other end portion of the hub is formed with a non-threaded ear 22. A clamp bolt 23 extends freely through the ear 22 and has threaded engagement with the ear 21 whereby the hub 16 may be contracted in diameter to tightly grip the body member of the beam and bind it thereon and thus prevent relative rotation of the parts. Whenever it is desired to make an adjustment of the beam heads 13 and 14 relative the beam barrel member 10 and to move them along the respective threaded portions 11 and 12 thereof, the clamp bolt 23 of each head is loosened to disengage the hub grip on the body member of the beam whereupon the head member is rotated by hand relative to the body member to obtain movement therealong to any desired position of adjustment. When this position is reached the heads are each locked in place by turning the clamp bolt 23 in the proper direction to contract the hub 16 on the beam barrel in the manner above described.

In order to prevent the ears 21 and 22 of the split portion 20 of the hub of the beam head from springing apart and opening too far when the clamp bolt 23 is loosened, the outer sides of the ears 21 and 22 adjacent to the outlying end of the hub 16 is cut away to form the ears 25 and 26, respectively, the ear 25 being provided with a threaded opening 27 while the ear 26 is formed with a non-threaded hole therethrough. A screw 28 having an enlarged head 29 extends through the hole in the ear 26 and is threaded into the ear 25 wherein it may be adjusted so that its head 29 will act as a stop to limit to a predetermined amount the extent of opening movement 75 of the hub when the clamp bolt 23 is loosened for

permitting lengthwise adjustment of the beam head.

In order to prevent uncovering of any of the screw threads which may become disposed between the head members from time to time upon endwise adjustment of the heads along the respective threaded portions of the body member, we have provided a cylindrical steel sleeve 30 which projects outwardly from the yarn engaging side face of the head member and is slidably mounted on the body member 10. Formed at one end of the sleeve 30 is a flange 31 which serves to attach the sleeve to the head member in loose, interfitting engagement therewith by means of an opening 32 therein, the walls of which are suitably undercut to accommodate the flange 31 whereby the beam head may be rotated and moved along the beam barrel without turning the sleeve thereon. The inner, cylindrical surface of the sleeve is accurately formed to the proper diameter and size so as to provide a smooth sliding fit on the beam body member 10. To this end, the screw threads on the body member are preferably of the square type having top portions comprising sections of a true cylinder, which are arranged so as to be coincident with and constitute continuations of the outer, smooth, cylindrical surface of the beam body member. Also, the sleeve 30 is preferably made of such length that it will extend lengthwise along the body member to completely cover the screw threads thereof when the head members have been fully adjusted to their extreme positions toward the ends of the barrel.

In order to apply friction to retard the rotation 35 of the beam, a sheave 35 is mounted upon each of the ends of the beam barrel 10 and suitably secured thereto, the sheave being of any well known construction and provided with a suitable shaft 36 for supporting the beam for rotation. 40

In Figs. 8 and 9, a modified beam construction is illustrated in which the body member of the beam is of a generally cylindrical tubular form pressed inwardly to provide a warp fastening means comprising a securing channel 37 having 45 a bottom wall 38 and side walls 39 at right angles to the bottom wall 38. In this construction, a sleeve 40 of generally cylindrical shape is split lengthwise to provide spaced ends 41 and 42 thereof which extend downwardly from the inner periphery of the sleeve into the warp receiving channel 37. A flange 43 formed at one end of the sleeve 40 serves to connect the sleeve to the head member 45, which is similar in construction to the head member 13 shown in Fig. 3, the flange having loose interfitting engagement therewith by means of an opening 46 the sides of which are suitably shaped to accommodate the flange 43 in a manner similar to that above mentioned.

In the modification shown in Fig. 10, the beam barrel 48 is provided with a warp end securing channel 49 and a split sleeve 50 is slidably mounted on the barrel with one of the ends 51 of the split parts extending into the channel 49. In 65 this construction the sleeve 50 is not anchored to the head member 52 but instead it loosely cooperates therewith in which one of its ends contacts with the warp engaging side of the head member so that upon turning the head in order 70 to move it along the barrel and away from the end of the beam, the sleeve 50 will be caused to slide without rotation along the body member of the beam. However, when the head adjusting movement is endwise toward the end of the 75

beam it will then be necessary to slide the sleeve 50 by hand axially along the barrel to bring the end again into contact with the yarn engaging side of the head member before winding the ends 5 of the warp on the barrel of the beam. The head 52 may be of any well-known construction, such as an annular plate member 53 and a split clamping hub 55, as shown in Fig. 10 of the drawing, the latter being in threaded engagement 10 with the barrel 48.

The foregoing description is directed solely towards the construction illustrated, but we desire it to be understood that we reserve all the privileges of resorting to any mechanical changes 15 to which the device is susceptible, the invention being defined and limited only by the terms of the appended claims.

We claim:

1. In a beam, a body member provided with 20 a screw threaded portion therealong, a head member embracing said body member and having a portion engageable with the threads on said body member for causing said head member to move axially of said body member upon 25 relative rotation of said members, means loosely attached to said head member and movable along said body member and of such length that the threads of said body member disposed under the layers of the warp may be covered at all times 30 regardless of the position of adjustment of the head member, and means to bind said head member on said body member to prevent relative movement of said members.

2. In a beam, a tubular body member provided 35 with a screw threaded portion therealong, a head member having a hub substantially fitting said body member and bearing thereon, threads on the inner surface of said hub member and engageable with the threads on said body member 40 for causing said head member to move axially of said body member upon relative rotation of said members, a sleeve cooperating with said head member and movable along said body member and of such length that the threads of said 45 body member disposed under the layers of the warp may be covered at all times regardless of the position of adjustment of the head member, and means to contract said hub to bind it on said body member and prevent relative movement 50 of said head and body members.

3. In a beam, a tubular body member provided 55 with a screw threaded portion therealong, a head member having a hub substantially fitting said body member and bearing thereon, threads on the inner surface of said hub member and engageable with the threads on said body member for causing said head member to move axially of said body member upon relative rotation of said members, a sleeve loosely attached to said 60 head member and movable along said body member and of such length that the threads of said body member disposed under the layers of the warp may be covered at all times regardless of the position of adjustment of the head member, 65 and means to contract said hub to bind it on said body member and prevent relative movement of said head and body members.

4. In a beam, a tubular body member provided 70 with a screw threaded portion therealong, a head member having a hub substantially fitting said body member and bearing thereon, threads on the inner surface of said hub member and engageable with the threads on said body member for causing said head member to move axially 75 of said body member upon relative rotation of

said members, a sleeve having a flange loosely attached to said head member and movable along said body member and of such length that the threads of said body member disposed under the layers of the warp may be covered at all times 5 regardless of the position of adjustment of the head member, and means to contract said hub to bind it on said body member and prevent relative movement of said head and body members.

5. In a beam, a tubular body member provided 10 with a screw threaded portion therealong, a head member having a hub substantially fitting said body member and bearing thereon, threads on the inner surface of said hub member and engageable with the threads on said body member for causing said head member to move axially of said body member upon relative rotation of said members, a sleeve projecting 15 outwardly from the yarn engaging face of said head member and movable along said body member and of such length that the threads of said body member disposed under the layers of the warp may be covered at all times regardless of the position of adjustment of the head member, and means to contract said hub to bind it on 20 said body member and prevent relative movement of said head and body members.

6. In a beam, a tubular body member provided 25 with spaced screw threaded portions, a pair of head members, one on each of said portions, 30 said head members each having a hub embracing said body member and provided with a threaded inner surface engageable with the threads on said body member for causing said head members to move axially along said body member upon 35 relative rotation of said members, sleeves loosely 40 engaging each of said head members and movable along said body member and of such length that the threads of the respective threaded portions of the body member disposed between the head members may be covered at all times regardless 45 of the position of adjustment of the head members, and means to contract each of said hubs to bind it on said body and prevent relative movement of said head and body members.

7. In a beam, a tubular body member provided 50 with spaced screw threaded portions, a pair of head members, one on each of said portions, said head members each having a hub embracing said body member and provided with a threaded inner surface engageable with the threads on said body member for causing said head members to move axially along said body member upon relative rotation of said members, sleeves having a flanged portion loosely engaging 55 each of said head members and movable along said body member and of such length that the threads of the respective threaded portions of the body member disposed between the head members may be covered at all times regardless of the 60 position of adjustment of the head members, and means to contract each of said hubs to bind it on said body and prevent relative movement of said head and body members.

8. In a beam, a tubular body member provided 65 with spaced screw threaded portions, a pair of head members, one on each of said portions, said head members each having a hub embracing said body member and provided with a threaded inner surface engageable with the 70 threads on said body member for causing said head members to move axially along said body member upon relative rotation of said members, sleeves having a flanged portion loosely engaging 75 and projecting outwardly from the yarn engag-

- ing face of each of said head members and movable along said body member and of such length that the threads of the respective threaded portions of the body member disposed between the head members may be covered at all times regardless of the position of adjustment of the head members, and means to contract each of said hubs to bind it on said body and prevent relative movement of said head and body members.
9. In a beam, a tubular body member provided with a screw threaded portion therealong, a head member having a hub substantially fitting said body member and movable thereon, threads on the inner surface of said hub member and engageable with the threads on said body member for causing said head member to move axially of said body member upon relative rotation of said members, a sleeve cooperating with said head member and movable along said body member and of such length that the threads of said body member disposed under the layers of the warp may be covered at all times regardless of the position of adjustment of the head member, and means adapted to prevent relative movement of said head and body members.
10. In a beam, a body member provided with a screw threaded portion and a longitudinal groove therealong, a head member embracing said body member and having a portion engageable with the threads on said body member for causing said head member to move axially of said body member upon relative rotation of said members, means loosely attached to said head member and movable along said body member with the head member and of such length that the threads of said body member disposed under the layers of the warp may be covered at all times regardless of the position of adjustment of the head member, said means also having a portion thereof positioned in said groove and means to bind said head member on said body member to prevent relative movement of said members.
11. In a beam, a body member provided with a screw threaded portion and a longitudinal groove therealong, a head member having a hub substantially fitting said body member and movable thereon, threads on the inner surface of said hub member and engageable with the threads on said body member for causing said head member to move axially of said body member upon relative rotation of said members, a sleeve cooperating with said head member and movable along said body member and of such length that the threads of said body member disposed under the layers of the warp may be covered at all times regardless of the position of adjustment of the head member, a portion thereof positioned in said groove and means to bind said head member on said body member to prevent relative movement of said members.
12. In a beam, a body member provided with a yarn securing slot therein and a screw threaded portion along part of said body, a sleeve embracing said threaded portion with its edges spaced and extending into said slot, said sleeve being slidable along the body to cover said screw threads while the warps are fastened in said slot and wound on the beam.
13. In a beam, a body member provided with a screw threaded portion and yarn fastening means therealong, a tubular sleeve of rigid material embracing said threaded portion but terminating short of complete encircling to provide a gap to expose said fastening means and of an internal diameter larger than the threaded portion to be slidable therealong to cover said screw threads while the warps may be fastened and wound on the beam.
14. In a beam, a body member provided with screw threaded portions at each end, and yarn fastening means therealong, sleeves of rigid material embracing said threaded portions but terminating short of complete encircling to provide a gap to expose said fastening means and of an internal diameter larger than the threaded portion to be slidable therealong to cover said screw threads while the warps may be fastened and wound on the beam over said threaded portions.

ROBERT V. OLSON.
